UNITED STATES PATENT OFFICE.

JAMES KERNES, OF CHICAGO, ILLINOIS, ASSIGNOR TO KERNES MANUFACTURING COMPANY, OF CHICAGO, ILLINOIS, A CORPORATION OF ILLINOIS.

DESIGN FOR A CLOCK CASE.

Application filed November 19, 1926. Serial No. 18,777. Term of patent 3½ years.

To all whom it may concern:

Be it known that I, JAMES KERNES, a citizen of the United States, residing at Chicago, in the county of Cook and State of Illinois, have invented a new, original, and ornamental Design for a Clock Case, of which the following is a specification, reference being had to the accompanying drawing, forming part thereof, in which—

Figure 1 is a front view of a clock case showing my new design, and,

Figure 2 is a side view thereof.

I claim:

The ornamental design for a clock case, as shown.

JAMES KERNES.
